Specification of Letters Patent.

Patented May 27, 1919.

Application filed December 18, 1916. Serial No. 137,483.

To all whom it may concern:

Be it known that I, CHARLES H. MARX, a citizen of the United States, and a resident of Chicago, in the county of Cook and State 5 of Illinois, have invented certain new and useful Improvements in Keyed Zithers, of which the following is a specification.

This invention relates to certain new and useful improvements in stringed musical instruments of the autoharp, cithern and zither types, and it consists in certain peculiarities of the construction, novel arrangement, combination and operation of the various parts thereof, as will be herein- 10 15 after more fully set-forth and specifically claimed.

The principal object of the invention is to provide a stringed musical instrument which has its strings on the under-side of the body 20 thereof and which shall be portable and compact in form, simple and inexpensive in construction, strong, durable and efficient in operation, with its parts so constructed, arranged and operating as to provide a series 25 of vibrating spring hammers for the strings of the instrument, which hammers may be manually operated so as to strike the strings once or repeatedly in rapid succession according to the length of time the keys of 30 the hammers may be depressed, thus producing tremolo or mandolin effect. Another object of the invention is to provide a stop for the key of each hammer or striker for the strings, so that, said hammers shall be 35 capable of striking their respective strings a single blow to produce a full clear note, and also of striking a number of times in quick succession to afford a sustained tremolo tone, or like that produced by a mandolin. A further object is to furnish an instrument of the above described general 40 character, which may be of such construction, that the instrument and its casing, or carrying-case, co-act with each other, or are 45 so related as to form a part of each other. A still further object is to greatly augment the volume of tone and to render more pleasing to the ear, the sounds or tones of the instrument, over those of the types in general 50 use at present. Still another object is to provide means for readily modulating the tones or sounds of the instrument.

Numerous other objects and advantages of the invention will be disclosed in the subjoined description and explanation.

In the accompanying drawings which serve to illustrate an embodiment of the invention:

Figure 1, is a plan view of an open casing, or carrying case showing the instrument 60 mounted in the body of the casing or case and forming a closure or part thereof, and also illustrating in full and dotted lines the holders for music sheets which may be used in connection with the instrument. 65

Fig. 2, is a fragmental plan view of the rear end of the instrument and part of the casing therefor, the hinged cover for the keys being removed.

Fig. 3, is a view in elevation of the rear 70 end of the instrument and its casing or container, showing the member which carries the strings of the instrument and the vibratory spring hammers or strikers raised from the casing ready for use and illustrating a scale on the rear end of the string and hammer carrying member. 75

Fig. 4, is an enlarged view, partly in section and partly in elevation taken on line 4—4 of Fig. 1, looking in the direction indicated by the arrows, showing the string and hammer carrying member of the instrument in about the position to which its rear end has been raised when ready for use, as shown in Fig. 3, said figure also 80 showing the means for adjustably supporting the string carrying member or sounding board so as to modulate the sound or tones of the instrument. 85

Fig. 5, is an enlarged fragmental bottom 90 plan view of the sounding board or the string and hammer carrying member, with said strings and hammers mounted thereon.

Fig. 6, is a detached perspective view of one of the keys and a part of one of the 95 spring shanks of the hammers which each of the keys carry.

Fig. 7, is a fragmental view partly in section and partly in elevation, taken on line 4—4 of Fig. 1, looking in the direction indicated by the arrows, showing a modification in the construction of the instrument with respect to its keys and the stop therefor. 100

Fig. 8, is a detached perspective view of similar parts to that shown in Fig. 6, illustrating a modification in the construction of the keys. 105

Fig. 9, is a side or end view of the pivot-bar showing a modification in the construction of the keys and in the means for stop. 110

ping the movement of the same so as to give vibration to the hammers.

Fig. 10 is a fragmental face view of a portion of the pivot-bar for the keys.

5 Fig. 11, is an enlarged view partly in section and partly in elevation of a fragment of the pivot bar and a part of one of the keys showing the means for supporting and securing the latter on the former, and for 10 keeping the keys from rattling.

Fig. 12, is a face view of a chart or sheet which may be used in connection with the instrument, and

15 Fig. 13, is a fragmental plan sectional view taken on line 13—13 of Fig. 4, looking in the direction indicated by the arrows.

20 Like numerals of reference refer to corresponding parts throughout the different views of the drawings.

25 The reference numeral 15 designates the box-like casing which may be provided with a lid or cover 16 secured thereto at one of its edges by means of hinges 17 or otherwise so as to close the casing 15 when desired. The casing 15 may be provided with a handle 18 and sockets 19 at one of its edges or sides, said sockets being for the reception of catches 20 which are mounted at suitable points on the side or edge of the lid 16 to engage the sockets 19 when said lid is turned to the position to close the case or casing. When the lid 16 is employed it may be provided with a holder 21 for the reception of music sheets 22 which can be inserted between said holder and lid 16 as will be readily understood by reference to Fig. 1 of the drawings. A similar device for a like purpose may be mounted on the inner surface of the bottom of the casing 15, as shown by dotted lines in Fig. 1, when the lid 16 is not used.

40 As shown in Figs. 1 and 4 of the drawings the sounding board or string and hammer carrying member 23 is located within the casing 15 and is secured thereto at one of its ends by means of hinges 24 or otherwise, so that it can be tilted or inclined as shown in Figs. 4 and 7 of the drawings, or if desired can be turned on its hinges or fasteners so as to reverse its position to enable the strings carried thereby to be turned and other parts mounted thereon to be adjusted or repaired. The rear end of the sounding board or member 23 is provided on its upper surface with a knob 25 to be used for lifting and adjusting said member, with respect to the sounding box or casing 15 and said board can be held in its adjusted positions by means of a support 26 and a pair of blocks 27 one of which is secured to each side of the casing 15 near its rear end. Each of the blocks 27 is provided with a series of notches 28 to receive the lower portion of 45 the support 26 which forms substantially

three sides of a rectangular figure when viewed from the rear end of the instrument and which has its ends pivotally secured to the sides of the sounding board 23 near the rear end thereof. The upper portion 70 of each of the blocks 27 is horizontally disposed to afford a rest for the board 23 when in its lowered or normal position, and each of said blocks may have in its upper portion a notch 28 to receive the lower portion of 75 the support 26, which latter notches are employed when it is desired to support the board 23 in its uppermost position for playing extra loud. Mounted transversely on the lower portion of the member or sounding board 23 is a strip of felt 29 or other cushioning material which is employed for the purpose to be presently explained. Near its rear end the board or member 23 is provided on its lower surface with a number of 80 hitch pins or screws 30 to which the strings 31 of the instrument are secured at their rear ends, the other ends of said strings being secured to tuning posts 32 which are secured to the lower surface of the board or member 23 85 instead of being arranged in the ordinary or well known way used on similar instruments heretofore. The strings 31 are supported on bridges 33 and 34 mounted on the lower surface of the board or member 23 and 90 said strings may be tuned by means of a key 35 which is for engagement with the tuning posts 32 in the ordinary way. In order that the tuning key 35 may be always kept in a convenient place for use the front 95 end of the casing 15 is provided with a hook 36 which is screwed into the casing 15 and can be turned so as to engage or disengage the handle of the key 35 which will be located in such a part of the casing as to be 100 out of the way of the posts 32 when the sounding board is in its lowermost or closed position. A little forwardly of the blocks 27, the floor of the casing 15 is provided with a pair of parallel bars 37 which are extended across the floor or bottom of the casing and are spaced apart as shown. Secured to the opposite sides of the bars 37 and extended over and across the same is a piece 110 of flexible material 38 which extends from one of the sides of the casing 15 to the other, so as to form a pneumatic chamber 39 between the bars 37, the supporting material 38 and the bottom or floor of the casing. This arrangement is used to arrest the vibrations 115 of the hammer heads after being manipulated and as a support for the hammers or strikers of the instrument as will be readily understood by reference to Figs. 4 and 7 of the drawings.

120 Secured transversely to the rear end of the board or member 23, is a pivot-bar or supporting-bar 40 which bar is by preference made of metal and projects slightly above and below the upper and lower surfaces re- 125

spectively of the sounding board or member 23 and may have on its face a printed scale-strip, either chromatic or diatonic, but is herein shown as a diatonic scale. This scale-
 5 strip may also show grouped strings tuned to produce chords. As will be clearly seen in Figs. 3 and 10 of the drawings the bar 40 is provided with a series of openings 41 which are located in a horizontal row near
 10 the lower edge of the bar 40, and each of said openings has its upper portion larger than its lower portion. It will also be seen that the bar 40 is provided with rearward and upwardly extended projections 42 near
 15 its lower edge and that each of these projections is provided with a character, such as, X, on its face. The openings 41 in the pivot-bar are for the reception and retention of the keys 43 for the vibrating spring
 20 hammers one of which is employed to strike two strings in the melody section of the instrument. Each of the keys 43 is made of non-resilient or stiff material and is formed near its middle on each of its sides with a
 25 notch 44 to receive the vertical walls 45 of the openings 41 in the pivot-bar. Each of the keys 43 is provided forwardly of the notches 44 therein with a pair of clips 46, and at their front ends with another pair
 30 of clips 47 which clips are for the purpose of clamping or holding the shanks 48 of the hammers 49 which shanks are made of resilient material such as thin strips of steel or metal. By means of these clips, which
 35 can be bent so as to clamp the shanks 48 on the hammers, it is apparent that said shanks will be firmly secured to the keys longitudinally thereon in such a way that the portions of the shanks projecting for-
 40 wardly from the clips 47 will have great resiliency or vibration when the keys are depressed and suddenly stopped. As shown in Figs. 4, 7, 9 and 11, the rear portions of the shanks 48 are located beneath the lower
 45 edge of the pivot-supporting bar 40 and as said portions are resilient they will clamp the keys 43 on said bar in such a way as to prevent vertical, dislocation thereof. The vertical walls 45 of the holes 41 in the pivot-
 50 bar 40 will prevent lateral movement of the keys, as is apparent. To insert the keys in the openings 41, of the pivot-bar therefor, the rear ends of the keys are placed in the enlarged portions of the openings 41 from
 55 the front surface of the pivot-bar, and the rear portions of the shanks 48 are placed beneath the lower edge of said bar. Now by forcing the keys rearwardly until the notches 44 therein are in position to receive
 60 the walls 45 of the contracted portions of the openings 41, it is obvious that the keys may be pressed downwardly between said walls so as to rest on the bottom edge of the openings 41, in which position they will be
 65 pivotally retained by the spring action of the shanks. As the keys must be stopped suddenly in their movement in order to cause vibration of the hammers 49 on the shanks 48, it is necessary to provide means for such sudden stoppage, and also to provide means 70 to prevent the hammers resting against the strings, and this can be done in numerous ways. In Figs. 4 and 6 of the drawings, I have shown each of the keys provided near its front end with a stop 50 which is by 75 preference punched out of the strip which forms the key, said stop which is punched out is small enough to pass between the strings without touching so it will not interfere with their vibration, and is extended 80 upwardly at a right-angle thereto, and located on the key at a proper position to strike the cushion 29 on the sounding-board when the keys are depressed as shown by dotted lines in Fig. 4 of the drawings. In- 85 stead of using the above described stops 50 for the keys, I may omit them from the latter and provide the sounding board 23 with a transversely extended stop 51 which may be padded on its lower surface and held at 90 a suitable distance below the board 23 by means of blocks 52 secured to the lower surface of the board 23 at its side edges, as will be readily understood by reference to Fig. 7 of the drawings. In Fig. 9, I have shown 95 still another modification in the stop for the keys which consists in providing the lower portion of the pivot-bar 40 with a rearwardly extended horizontal portion 40^a against the rear edge of which the keys 43 100 will strike when depressed as shown by dotted lines in the last-named figure. Hinged at one of its edges to the upper edge of the pivot-bar 40 is a plate 53 which serves as a cover for the front end of the 105 keys 43 when in the position shown in Fig. 1 of the drawings, and acts as a holder for the music sheet or sheets 54 when raised to the position shown in Figs. 4 and 7 in which position said plate will be sustained by the 110 handle or knob 25 on the sounding board. As it may sometimes be desirable to omit the lid or cover 16 of the carrying case 15, the rear portion of the sounding board or member 23 is provided near each of its corners 115 with a pivoted catch 55 to engage pins 56 on the casing 15 in order to hold the board or member 23 in its closed position and so as to form a closure for the casing 15 of the 120 sounding box.

From the foregoing, and by reference to the drawings, it will be clearly understood and readily seen that by reason of the improvements set forth a very compact and portable instrument will be afforded, which is self-contained or in other words, the carrying casing and the instrument co-act with each other in such a manner as to form essential parts of the instrument. By the 125 novel and improved construction which is 130

employed, the casing or carrying casing which is provided, need not be any larger or materially deeper than those employed for autoharps, citherns or zithers of the same size. If it is desired to lessen the weight of the casing, the lid 16, may be omitted, when as above set forth the sounding board or member 23 may be employed as a closure for the casing or sounding box; thus affording a complete stringed musical instrument of the character described, which is ready for instant use, and can be closed for transportation or shipment in such a manner that the parts of the instrument will be protected and prevented from vibration or from producing sounds. For it will be understood that the hammers 49 will rest on the stop or cushion 38, in such a way as to prevent them striking the strings 31, in the ordinary handling of the instrument when the sounding board 23 is in its closed position.

Referring now to Fig. 3, of the drawings, it will be understood that the key shown to the left of each of the groups will strike the heavy or lowest bass string of the chord, and the key to the right of each of the groups distinguished by a dot below the numeral, will strike the other three strings constituting the remainder of the chord. The strings of the chord section are placed so as to allow the stop 50 to pass them without touching and consequently interfering with the vibration of said strings.

In the foregoing description, that end of the instrument adjacent to the player or operator has been designated as the "rear end", and this term has been used for the sake of clearness, and without any intention of limitation.

It will be distinctly understood and clearly seen that by my improvements, a stringed musical instrument having the strings mounted on and below the sounding board or string carrying member of the instrument is provided, and that the striking members or hammers are also carried by and beneath said sounding board or member and arranged to strike the strings of the instrument on the bottom of said strings and with an upward stroke or strokes of the key or keys of the instrument, which are mounted and equipped for such movement at or near their rear ends. It is further obvious that the carrying casing 15, forms not only a receptacle for the instrument by means of which it will be protected and can be transported or carried, but also provides a sounding box which by reason of the relation therewith of the sounding board or member 23 and its musical strings, will augment sounds or tones of the instrument, which sounds or tones can be readily modulated from soft tones or sounds to louder ones by simple inclination and adjustment of the

sounding board or member with respect to the casing or sounding box.

To enable one who is not familiar with notes, to play pieces on this instrument, I have provided a chart, (see Fig. 12). This chart is to be placed above the keys 48, so that the character such as "X", on the chart will register with the clips 42. Then, begin reading at the arrow on the chart and follow the continuous line to the end. Wherever there is a black circular spot the key directly beneath the same should be depressed. The first circular spot represents the first note of the piece being played, the second circular spot the second note, the third circular spot the third note, and so on. The small dots beside the circles represent the time or the number of beats each circular spot is to receive: and the numeral beside some of the spots indicate which corresponding chord key is to be struck at the same time, thus producing the accompaniment to the melody.

While I have illustrated and described an embodiment of the invention in a form of construction for carrying it into effect, yet this is capable of variation and modification without departing from the spirit of the invention. I therefore, do not wish to be limited to the precise details of the construction as set forth and disclosed, but desire to avail myself of such variations, modifications and modes of its use as come within the scope of the appended claims.

Having thus fully described my invention, what I claim as new and desire to secure by Letters Patent is—

1. The combination of a zither, means for supporting said zither in an inverted position with the strings beneath the body thereof, a plurality of keys in operative relation to the zither below the strings, and hammers associated with said keys for striking the strings.

2. The combination of a zither, means for supporting said zither in an inverted position with the strings beneath the body thereof, a plurality of keys in operative relation to said zither and extending lengthwise of and below the strings, a pivot member attached to the zither and arranged crosswise of the strings and pivotally supporting said keys intermediate of the ends thereof, spring hammers projecting from the rear ends of said keys, and a stop to arrest the said keys upon depression of the front ends thereof.

3. The combination of a zither, means for supporting said zither in an inverted position with the strings beneath the body thereof, a plurality of keys extending lengthwise of and below the strings with their front ends projecting forwardly from beneath the front end of the zither, a pivot member attached to the zither and arranged crosswise

of the strings for pivotally supporting said keys intermediate of the ends thereof, the front ends of said keys projecting forwardly beyond the front end of the said zither, 5 spring hammers projecting rearwardly from the rear ends of said keys, and stops for arresting the movements of said keys in opposite directions about said pivot member.

4. The combination with an inverted 10 zither having the strings beneath the body thereof, of a plurality of manually operated hammers operatively associated with said zither and extending longitudinally of the strings for playing the same, and legs for 15 supporting said zither in position for the operation of the hammers.

5. The combination with an inverted zither having the strings beneath the body thereof, of a plurality of manually operated 20 hammers operatively associated with said zither and extending longitudinally of the strings for playing the same, and folding legs for supporting said zither in position for the operation of the hammers.

25 6. The combination of an inverted zither having the strings below the body thereof, a plurality of keys and associated spring hammers arranged below the strings, means for supporting said keys and hammers in operative relation to the strings, a casing having a bottom wall and end and side walls, means hinging the zither to the rear end wall of said casing so as when closed to lie normally within said end and side walls in substantial 30 parallelism with said bottom wall, and supporting means for supporting the front end of said zither when opened in a raised position.

7. A stringed musical instrument consisting of a carrying-case and a board connected thereto for movement to and from said case, musical strings mounted on the lower surface of the board and means carried by the board to play upon said strings.

40 8. In a stringed musical instrument, the combination with a box-like case, of a board movably connected to said case and adapted to close the same, musical strings mounted on said board and means carried by the board to play upon said strings.

45 9. A carrying-case having an opening therein and a stringed musical instrument connected to said case so as to movably operate in said opening whereby the case will act as 50 a sounding-box to increase the volume of the tone of the instrument, and means to modulate the tone or sounds of the instrument.

55 10. A carrying-case having an opening therein and a stringed musical instrument connected to said case so as to movably operate in said opening whereby the case will act as a sounding-box to increase the volume of the tone of the instrument, and means to adjustably support the instrument within the 60 case.

11. A carrying-case having an opening therein and a stringed musical instrument connected to said case so as to movably operate in said opening whereby the case will act as a sounding-box to increase the volume of the 70 tone of the instrument, a depending support mounted on the instrument near one of its ends to adjustably support said instrument within the opening of the case.

12. A carrying-case having an opening 75 therein and a stringed musical instrument connected to said case so as to movably operate in said opening whereby the case will act as a sounding-box to increase the volume of the tone of the instrument, a depending support 80 pivotally mounted on the instrument near one of its ends, and a notched block within the case below the instrument to engage said support.

13. A carrying-case having an opening 85 therein and a stringed musical instrument connected to said case at one of its ends so as to movably operate in said opening whereby the box will act as a sounding-box to increase the volume of the tone of the instrument, a depending support 90 pivotally mounted on the instrument near its free end, and a rearwardly and upwardly beveled block within the case below the instrument and having means on its beveled surface to engage 95 said support.

14. A carrying-case having an opening 100 therein and a stringed musical instrument connected to said case at one of its ends so as to movably operate in said opening whereby the case will act as a sounding box to increase the volume of the tone of the instrument, a depending support 105 pivotally mounted on the instrument near one of its ends, and a rearwardly beveled block within the case at each side thereof below the instrument, each block having a plurality of notches to receive said support.

15. A stringed musical instrument consisting of a case and a board connected thereto for movement toward and from said case, musical strings strung on the lower surface of the board, a series of vibratory spring hammers mounted on the rear end of the board and operable to strike the lower surface of said strings, and means to support the board at a distance from the floor of the case.

16. A stringed musical instrument consisting of a case having a cushioned hammer 110 stop extended across the upper surface of its floor near one end thereof, a board connected at one of its ends to the end of the case opposite said stop for pivotal movement toward and from said case, musical strings strung 115 on the lower surface of the board, and a series of vibratory spring hammers mounted on the rear end of the board and operable to strike the lower surface of said strings and adapted to normally rest on said stop. 120 125 130

17. The combination with a portable case having a hammer rest mounted across the floor of the case near one end thereof, of a stringed musical instrument connected with said case at one of its ends, a series of vibratory spring hammers mounted on the instrument so as to be capable of striking the strings and normally lying on the rest. 45
18. The combination with the body of a stringed musical instrument having its strings strung on the bottom, a series of vibratory spring hammers mounted at its rear end, said hammers having projections which pass between the strings when the hammers are manipulated and engage the body of the instrument, said projections acting as stops and preventing the hammer heads from resting on the strings, thus causing them to vibrate and strike the strings repeatedly, producing tremolo. 50
19. The combination with a stringed musical instrument, of a pivot-bar arranged thereon transversely of the strings and having a series of openings therein, said openings being larger in their upper portions than in their lower portions and having vertical walls in their lower parts, a key located in each of said openings and each having notches in its edges in front of the finger piece to receive the vertical walls of the reduced portion of the opening in which it is located, a spring shank attached to each key to project from the front end thereof and having on its free end a hammer. 55
20. The combination with a stringed musical instrument, of a plurality of pivoted keys, a plurality of spring hammers supported by said keys and means between the keys and the body of the instrument for stopping and holding the hammers away from the strings. 60
21. The combination with a stringed musical instrument, of a pivot bar having an opening therein provided with vertical walls, a key located in said opening and having a notch in each of its edges in front of its finger piece to receive the vertical walls of said opening, a spring shank fastened to said key and extended at its rear portion under and against the pivot bar to steady and ease the fall of the key, and a hammer on the front end of said shank. 65
22. The combination with an under strung stringed musical instrument, of a case connected to said instrument so as to permit of their movement toward or from each other and so that the casing will receive said instrument, a plurality of vibratory spring hammers operatively mounted on one end of the body of the instrument and adapted to strike said strings, and a hammer rest arranged for engagement by the heads of said hammers, said rest comprising a pair of spaced apart bars transversely mounted on the floor of the casing forwardly of the points at which the hammers are mounted on the instrument, and a layer of cushioning material stretched across said bars and separated from the floor of the casing by a closed chamber. 70
23. A key for stringed musical instruments consisting of a non-flexible piece provided with means for securing thereto a silent shank or stem, said stem engaging said securing means and extended longitudinally with respect to the key, a hammer on the free end of the stem, said key having a projection extended at an angle therefrom to pass between the strings of the instrument and to strike the body thereof, so as to act as a stop and prevent the hammer from remaining on the strings thus allowing the hammer to vibrate and strike the string repeatedly for the purpose of producing tremolo. 75
